UNITED STATES PATENT OFFICE.

JOHN FRAZER WARNER, OF MUNCIE, INDIANA.

CONTROLLING MECHANISM FOR VARIABLE-SPEED GEARING.

No. 927,698.

Specification of Letters Patent.

Patented July 13, 1909.

Application filed December 31, 1906. Serial No. 350,234.

To all whom it may concern:

Be it known that I, JOHN FRAZER WARNER, a citizen of the United States, and a resident of Muncie, Delaware county, in the State of Indiana, have invented a new and useful Improvement in Controlling Mechanism for Variable-Speed Gearing, of which the following is a specification.

My invention relates to improvements in operating levers for variable speed gearing, through which several different speeds may be obtained by certain shifts of the gears in the variable speed gear set, and has for its object to provide certain new and useful improvements in the construction, form, and arrangement of parts whereby several variations of speed may be easily determined, engaged and controlled by certain movements of the actuating lever as the operator may 20 select.

A further object is to provide a suitable supporting frame, a guide plate having a single slot, a pair of sublevers with suitable axles and an actuating lever having both a 25 lateral and rotary motion relatively to the said axles.

A further object is to provide a device of the above character in which independently operated sublevers are held in position 30 by a suitable guide plate, supported on a frame in which is journaled the axles of the sublevers so as to make a selective lever set complete in itself.

A further object is to provide a selective 35 control lever set, which has a guide plate having a single slot adapted to admit of at least four movements to the two sublevers to the selected positions controlled by the actuating lever.

40 A further object is to provide a selective control lever set, which has a guide plate having a single slot and a neutral position for the actuating lever so as to lock both sublevers when the actuating lever is in 45 neutral position.

A practical embodiment of my invention is represented in the accompanying drawings, in which—

Figure 1 is a sectional view of my selective lever set. Fig. 2 is an end view showing the side of the guide plate. Fig. 3 is a top view of the frame and guide plate only all other parts removed. Fig. 4 is a perspective view of the guide plate. Fig. 5 is a face view of one of the sublevers show-

ing the lock spring removed. Fig. 6 is an edge view of one of the sublevers showing the lock spring riveted to it. Fig. 7 is an edge view of the lock spring. Fig. 8 is a face view of the lock spring. Fig. 9 is a perspective view of the shifting key. Figs. 10 and 11 show a modification of the bracket or means of support for the guide plate. Figs. 1 and 10 show a movement of the control lever 6, which I shall term in this specification and claims, a lateral movement, as it is a movement longitudinally of, the axial centers of the sublevers, and likewise Figs. 2 and 11 show a movement of the control lever 6 which I shall term in this specification and claims a rotary movement, as it is a movement partly around the axial centers of sublevers, so where these movements are mentioned it will be known what they are. Said levers are used in connection with a 75 guide plate having a single slot, as a multiplicity of slots is confusing to the operator and often difficult to engage.

1 is a bracket adapted to bolt on to the regular frame of an automobile by the flange 80 13 and holes 31. The top portion of the bracket has two ears 33 which are secured to the guide plate 34 by screws 20. The guide plate 34 is preferably a curved plate having a single opening 35 with flanges 85 36, 37, 22 and 22, and ends 27 and 28, with notches 21 and 29 in the flanges 36 and 37.

3 and 4 are sublevers, secured permanently to the tube 13 and axle 14 respectively. The sublevers 3 and 4 have their top 90 ends guided by the flanges 36, 37, 22 and 22, so as to allow them to operate through an arc, and are provided with suitable openings, 23, 23, preferably the same width as the notches 21 and 29, and adapted to register therewith, and to be locked by the lock springs 8 and 9 which are secured to the sublevers by screws 10 and 11. The lock springs have suitably shaped ends so bent or formed as to adapt themselves as locking 100 devices to hold the sublevers in the central or neutral position, and to make the openings 23, 23 register with the notches 21, and 29.

The control or selective lever 6, is pivoted 105 to the bearing block 5, by a pin 7, and carries a cross member or key 38, secured by a suitable pin 12. Said cross member 38, has suitable notches 18 and 19 adapted to register with the flanges 36 and 37 when the 110

control lever 6 is moved sidewise as shown in dotted lines 16 and 17 respectively, in Fig. 1.

On some automobiles it may be necessary 5 to use other forms of brackets to support the guide plate; for instance the guide plate may have legs cast integrally therewith as shown in Fig. 11 at 39 and 40, or it may have other means of support as by the 10 frame of the automobile, and it may be made flat on top instead of curved or a variety of ways.

The bearing 41 shown in Fig. 11 may be used for supporting the sublevers or some 15 other form of bearing may be substituted, but it is obvious that the guide plate should be held permanently and in a certain relation to the axial center.

The operation of my selective control 20 lever set is as follows: The control lever 6 is held in neutral position by the lock springs on the sublevers as shown in Fig. 1. Supposing that the axle 14 be coupled to a variable speed gear set in such a way as to give 25 a slow or first speed by moving it one way and a reverse motion by moving it in the opposite direction, and the tube 13 so connected as to give the third and second speeds by front and back movements respectively in positions as shown in Fig. 3; the reverse motion of the gears is obtained 30 by pressing the control lever 6 to the right as shown in dotted lines 16, so that the notch 19 in key 38 registers with the flange 37, when the control lever 6, is locked to the sublever 4, by means of key 38, and the pair thus engaged are actuated forward or backward. The pair are held locked by the flange 37. A similar movement is made by 35 pressing the control lever 6 over to a position shown in dotted lines 17, at which time the sublever 3 is engaged to the control lever 6 by key 38, and the forward and backward movements give respectively the 40 third and second speeds. It is clear to see that when the control lever is brought to the central or neutral position, the springs 45 8, and 9, equalize themselves against the opposite ends of the key 38, which forms a lock for both the control lever and the two sublevers. To operate my selective control lever set it is therefore necessary to give the control lever two movements in the 50 single slot 35; that is actuate it to either position 16 or 17, and then shift it forward or backward. It is also obvious that I can 55 select or obtain any position or speed from the neutral point without going through or passing any other operating position, and 60 without latches, thumb pushes or finger controlled parts on the control lever. It is also obvious that my selective control lever set is self locking, and is a reliable automatic locking lever set. I do not intend to 65 say that this device can not operate any other

way, nor do I mean to limit myself to this exact form of construction, especially with regard to the form of support. Details of construction may be varied without departing from the principles of my invention. 70

Having described my invention what I claim as new and desire to secure by Letters Patent is:—

1. In a device of the class described a guide plate having a single slot therein, 75 downturned notched flanges integral with the plate, independently adjustable sublevers, an actuating lever and means carried thereby for engaging either of the sublevers and also engaging the appropriate flange to 80 lock the actuating lever in engagement with the proper sublever.

2. In a controlling mechanism a plurality of sublevers, a spring secured at one end to each sublever, a guide plate having a single 85 slot therein, a control lever, and a key secured to said control lever adapted to selectively engage either sublever, said guide plate provided with means for engaging in slots in the key for locking the control lever 90 in engagement with one of the sublevers.

3. In a device of the class described concentric shafts, a sublever rigidly connected with each shaft and each provided with a recess, a guide member provided with a slot and notched flanges at the slot, an actuating lever, means rigidly secured thereto adapted to extend through the slots in the flanges and engage in the recess in the appropriate sublevers, said means provided with notches 100 each adapted to receive the appropriate flange therein and a spring secured to each sublever and bearing against the aforesaid means.

4. In a speed controlling mechanism the 105 combination with sublevers of individual axles, a bracket carrying said axles, a control lever mounted to swing in both a longitudinal and transverse plane, a guide plate having a single slot, flanges on said guide 110 plate and means secured to the control lever for actuating the sublevers selectively and adapted to coact with the flanges for holding the control lever in operative engagement.

5. In a controlling mechanism for variable speed gearing, the combination with a bracket, of two sublevers provided with openings, carried by the said bracket, a control lever, a guide plate having a single slot, 115 said guide plate having flanges in which are 120 notches adapted to register with openings in said sublevers, locking devices on said sublevers and means for actuating said sublevers, said means adapted to engage said flanges selectively.

6. In a device of the class described concentric shafts, a lever rigidly secured to each, a longitudinally and transversely movable operating lever, a key secured thereto adapted to selectively engage any of said levers 130

secured to the shafts and a guide element notched to permit the key engaging the appropriate lever and coacting with the key to lock the operating lever in engagement with 5 the appropriate sublever.

7. In a speed controlling mechanism the combination with a bracket, a slotted member secured thereto, an actuating lever longitudinally and transversely adjustable in 10 the slot, flanges integral with the slotted member providing channels, sublevers, each having a recess therein, one sublever for each channel and each having one end engaged between two of the flanges, means on the 15 actuating lever for engaging in the recess in any of the sublevers and coacting with one of the flanges to lock the lever in engagement with the appropriate sublever.

8. The combination in a selective speed 20 controlling device for slidable gearing, of a means of support, a fixed guide plate having only one slot, sublevers and axles, said axles journaled in said support, a control lever pivotally mounted on one of said axles, a 25 projection carried by said control lever, said projection adapted to operatively engage an opening in the respective sublevers, and the guide plate having means for holding said control lever in operative engagement with 30 said respective sublevers, said control lever mounted to swing in both a longitudinal and transverse plane in said single slot.

9. The combination in a selective speed 25 controlling device for slidable gearing, of a bracket, a fixed guide plate having a single slot, sublevers, locking springs carried by said sublevers, said locking springs adapted

to engage in notches in the guide plate, said sublevers adapted to be selectively engaged, means for operating said sublevers selectively, and the guide plate having flanges adapted to engage in notches in the means for operating the sublevers. 40

10. In a device of the class described concentric shafts, a sublever secured to each 45 shaft, a guide plate provided with a slot and notched flanges, an actuating lever, projections extending from the actuating lever adapted to engage the respective sublevers and an upturned end on one of the projections adapted to engage on each side of one 50 of the flanges.

11. In a device of the class described a guide member having notched flanges, sublevers, springs secured thereto, an actuating 55 lever and means secured thereto adapted to force either spring outwardly from the flanges and to engage the respective sublever and adapted to engage one of the flanges to lock the actuating lever to the respective 60 sublever.

12. In a device of the class described concentric shafts, a sublever secured to each shaft, each provided with a notch, an actuating lever, a guide plate having depending 65 notched flanges, and projections extending oppositely from the actuating lever each adapted to engage in the notch in the appropriate sublever.
